UNITED STATES PATENT OFFICE.

OTTO WIEDEKE, OF DAYTON, OHIO, ASSIGNOR OF ONE-HALF TO GUSTAV WIEDEKE, OF DAYTON, OHIO.

TUBE-EXPANDER.

1,102,993.

Specification of Letters Patent.

Patented July 7, 1914.

Application filed November 13, 1913. Serial No. 800,872.

To all whom it may concern:

Be it known that I, OTTO WIEDEKE, a citizen of the United States, residing at Dayton, in the county of Montgomery and State 5 of Ohio, have invented certain new and useful Improvements in Tube-Expanders; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to new and useful improvements in tube expanders or implements for expanding the ends of tubes in the tube sheets of boilers.

The invention is especially adapted for expanding arch tubes of locomotive boilers which, owing to the presence of the water legs, requires an expander of comparatively greater length in order to reach the end of the arch tube from the outside of the boiler.

25 The objects of the invention are several, principally among which are to provide means in this type of tube expander for preventing the expanding rollers from dropping inwardly and becoming displaced from the 30 tool when the mandrel is withdrawn; and to provide convenient means for enabling the operator to determine the extent of insertion of the mandrel as the tool is being operated to expand the tube.

35 Preceding a detail description of the invention, reference is made to the accompanying drawings, of which—

Figure 1 is a longitudinal side elevation of a tube expander constructed in accordance 40 with my invention; Fig. 2 is a longitudinal section of the same on the line *e—e* of Fig. 1; Fig. 3 is a section on the line *a—a* of Fig. 2; Fig. 4 is a section on the line *b—b* of Fig. 2; Fig. 5 is a section on the line *c—c* of Fig. 2; Fig. 6 is a view of the mandrel; Fig. 7 is a section on the line *d—d* of Fig. 2; Fig. 8 is an enlarged sectional view of the head of the tool showing the manner of inserting the rollers; and Fig. 9 is a detail view of the 50 ring which is instrumental in holding the rollers in position.

In a detailed description of the invention, similar reference characters indicate corresponding parts throughout the specification and drawings.

The body of the tool is lengthened as compared with the ordinary tube expander because of its being designed to extend through the water leg of a boiler to expand arch tubes as before stated. The said body consists of a shank or barrel 1 terminating at its forward end in a head 2 provided with the usual openings 3 for the expanding rollers 4 to project through in making contact with the surrounding surfaces of the boiler tube. The said barrel is further provided with a double row of openings 5 which will be again referred to in connection with a guard 6. The mandrel 7 is insertible throughout the length of the barrel in the 60 usual manner and is made tapered to form a wedge-like engagement with the inner sides of the expanding rollers. Referring to the openings 3 through which the rollers project, the outer longitudinal edges 8 of said 65 openings are curved inwardly in the usual manner to prevent the rollers from falling out of the head. The means for preventing said rollers falling inwardly when the mandrel is withdrawn is as follows: In order to 70 facilitate and make possible the placing of the expanding rollers in position and maintaining them in such position against any tendency to fall inwardly within the head when the mandrel is withdrawn, the inner 75 surfaces 10 which extend from straight surfaces 11. The tapered surfaces 10 permit the rollers to be inserted in the interior of 80 the head 2 and to be subsequently raised to a parallel position which is the operative position of the rollers as is shown in Figs. 1 and 2. In Fig. 8, the dotted lines show the manner of inserting said rollers. When in 85 the operative position, the straight surfaces 11 form shoulders which maintain the rollers against any lengthwise shifting while in operation. Extending from the inner longitudinal margins of the roller openings are 90 inwardly projecting shoulders 9 which extend from the inner terminals of the tapered surfaces 10 a sufficient distance to support the rearward ends of the rollers from falling 95 inwardly when the mandrel is withdrawn. In inserting the rollers in the manner shown in dotted lines in Fig. 8, the rearward end of each roller is moved in position above the shoulders 9, such movement being permitted by the tapered surfaces 10. The ends 100 105 110

of the rollers 4 opposite the shoulders 9 are provided with pins or projections 19 which, when the rollers are in operative position, lie in pockets 12 at the ends of the openings 5 3. The inner ends of the pockets 12 are adapted to be closed by a resilient ring 17 which lies in a suitable annular recess 18 on the interior of the head 2. The said ring 17 lies in the path of the pins 19 thereby maintaining, in connection with the shoulders 9, the rollers 4 in the pockets 3 when the mandrel 7 is withdrawn. The length of the pockets 12 is such that the rollers 4 may have a radial movement during the process of expanding the tube. The resilient ring 17 is sprung into the recess 18 through the central opening in the head of the tool.

The guard or ring 6, before referred to, is inclosed by the usual bearing or collar 13. 20 Heretofore, so far as I am aware, it has been the practice to unite the said guard to the body of the tool by means of set screws which engage the outer circumference of the barrel and are provided with heads which 25 project beyond the circumference of the guard. Such means are often found objectionable in manipulating the implement because of the fact that the heads of the screws frequently come in contact with parts of the 30 boiler head when rotating the implement in the operation of expanding the tubes. With the present improvement, the set screws 14 are reduced in diameter at their inner ends, as at 15, to enable said screws to enter the 35 openings 5 in the barrel and to be inserted below the circumference of the guard 6. A number of such openings 5 are provided in the barrel to enable the collar to be shifted to the desired position and there united to 40 the barrel. To permit of a finer adjustment of the guard 6 without decreasing the strength of the screw at 15 or the barrel 1, the said openings are staggered in a double 45 row as is shown in Fig. 1. In this connection the present device is an improvement over the device shown and described in my co-pending application, Serial No. 791,505, filed Sept. 24, 1913.

In manipulating the implement, it will be 50 understood that the mandrel 7 is forced into the barrel as the work of expanding progresses in order to exert a progressive outward force on the expanding rollers. Heretofore, so far as I am aware, the operator 55 had no guide to direct him in this matter in order that he might know the extent of the

insertion of the mandrel. In order to overcome this objection, I have provided on the outer end of the mandrel a series of circular lines 16 of equi-distance. These lines form 60 an index by which the operator may know the extent of the insertion of the mandrel necessary to accomplish the expansion of the tube.

Having described my invention, I claim. 65

1. A tube expander, comprising an elongated cylindrical body terminating at one end in a head provided with the necessary roller apertures, the rearward end walls of said apertures being tapered outwardly and 70 having inwardly lying shoulders extending therefrom, a series of expanding rollers confined within said apertures, the rearward ends of which lie between said shoulders and the outer longitudinal edges of the apertures, 75 a pin extending from one end of each of said rollers, and means in the head in a position to be engaged by said pins and supporting the outer ends of said rollers.

2. A tube expander, comprising a cylindrical body terminating at one end in a head provided with roller openings, the rearward walls of said openings being tapered and the rearward sides having shoulders extending inwardly therefrom, a series of expanding 80 rollers within the openings in said head, an axial pin extending from one end of each of said rollers, said head being provided with pockets at the ends of said openings to receive said pins, and means in said head in a 85 position to be engaged by said pins and supporting the outer ends of said rollers.

3. A tube expander, comprising a cylindrical body terminating at one end in a head provided with roller openings, the rearward 90 walls of said openings being tapered and the rearward sides of said openings having shoulders extending inwardly therefrom, a series of expanding rollers mounted therein, an axial pin extending from one end of each 100 of said rollers, said head being provided with pockets at the ends of said openings to receive said pins, and a resilient ring mounted in said head in a position to be engaged by said pins and adapted to support the outer 105 ends of said rollers.

In testimony whereof I affix my signature, in presence of two witnesses.

OTTO WIEDEKE.
